UNITED STATES PATENT OFFICE

JAMES J. O'CONNELL, OF ROCHESTER, NEW YORK.

DIRECTION-INDICATING SIGNAL.

1,089,950.

Specification of Letters Patent. Patented Mar. 10, 1914.

Application filed May 21, 1913. Serial No. 769,111.

To all whom it may concern:

Be it known that I, JAMES J. O'CONNELL, a citizen of the United States, residing at Rochester, in the county of Monroe and State of New York, have invented certain new and useful Improvements in Direction-Indicating Signals; and I do hereby declare the following to be a full, clear, and exact description of the invention, such as will enable others skilled in the art to which it appertains to make and use the same.

This invention relates to new and useful improvements in direction indicating signals for automobiles, and as its principal object aims to provide a device of this character which may be electrically operated from the driver's seat to indicate to the driver of an oncoming vehicle that the signal carrying car contemplates a left turn, right turn, or a stop, as the case may be.

A further object is to combine a signal of the above type with the ordinary rear danger light, such as is universally required by all State laws.

A further object is to provide a signal constructed in such manner that the right, left, stop, and rear light characteristics and license plate may all be illuminated by a single electric lamp.

A still further object is to equip the signal with a number of sliding shutters operated by electromagnets, which are controlled from the driver's seat, the shutters being so arranged that they may be independently operated to selectively illuminate the various elements of the signal.

The above and additional objects are accomplished by such means as are illustrated in the accompanying drawings, described in the following specification, and then more particularly pointed out in the claims which are appended hereto and form a part of this application.

With reference to the drawings, wherein I have illustrated the preferred embodiment of my invention, as it is reduced to practice, and throughout the several views of which similar reference numerals designate corresponding parts: Figure 1 is a front elevation of the signal with the license plate attached in assembled position. Fig. 2 is a section on the line 2—2 of Fig. 1. Fig. 3 is a section on the line 3—3 of Fig. 1. Fig. 4 is an interior elevation with the back plate removed. Fig. 5 is a section on the line 5—5 of Fig. 2. Fig. 6 is a section on the line

6—6 of Fig. 1. Fig. 7 is a diagrammatic view of the electrical wiring system. Fig. 8 is a detail view of the frame employed in mounting the glass signal plates.

Proceeding now to the description of the drawings, the numeral 10 designates a cylindrical casing, on the rear edge of which, and circumferentially spaced from each other, as indicated at 11 in Fig. 5 and Fig. 2, are formed a number of internally screw threaded lugs, which, in the assembled position of the casing, project through apertures formed in a base wall 12, and are held in fixed position by burs or nuts 13. The casing 10 is formed with a circular face plate 14, which is formed with three rectangular openings, individually designated in Fig. 1 by the numerals 15, 16 and 17. An elongated slot is cut in the face plate 14, as at 18, in Fig. 1, and the plate is stamped out to produce the reflecting shields 19 and 20, which are respectively bent to extend exteriorly and interiorly of the casing, in order to reflect the light from an electric lamp 21 secured centrally of the base plate onto a license plate 22 which is bolted or otherwise secured to a fastening strap 22', fixed on the lower portion of the face plate 14. The particular function of the members 19 and 20 will be hereinafter more fully disclosed.

Centrally of the face plate 14 and in the space formed between the members 15, 16 and 17, a circular opening is formed, in which a red tail light glass 23 is arranged. In the three openings 15, 16 and 17 are respectively arranged the three signal glass plates 24, 25 and 26. As most clearly shown in Fig. 1, these three glass plates are preferably colored, the member 24 being purple, the member 25 red, and the member 26 green. Arrows are formed in the glass plates in the usual manner, and at the end of the arrow shafts are placed the direction indicating characteristics R, S, and L, respectively, designating a right turn, a stop, and a left turn. The glass plates 23, 24, 25 and 26, and license plate 22, are all designed to be illuminated by a single electric lamp, above referred to by the numeral 21. The tail signal 23 and the license plate 22 are designed to be illuminated at all times, while the invention contemplates the independent illumination of the three direction indicating signal glass plates 24, 25 and 26, in the manner now to be disclosed.

It will be observed by reference partic-

ularly to Fig. 3, that the plates 24, 25 and 26 are arranged to cover the openings 15, 16 and 17, by being mounted in substantially U-shaped metallic frames, one of which is 5 designated as an entirety by the numeral 27, in Fig. 8. The frames 27 may be soldered or otherwise secured in any desired manner to the face plate 14. Each of the glass plates of the signal plates 24, 25 and 10 26 is equipped with a casing, designated as entireties by the numerals 28, 29 and 30. By reference to Fig. 4 it will be observed that the casings 28, 29 and 30 are similar in construction, and it is therefore deemed 15 necessary to describe only one of them in detail, the member 30 being chosen in this instance. Each casing includes a rear wall 31, and divergent top and end walls, respectively designated by the numerals 32, 20 33 and 34. The casings are mounted on the inner face of the plate 14, by being soldered or otherwise secured, and are all arranged with their open ends adjacent the center point of the casing, thus making 25 each of the chambers A, B and C, respectively formed by the casings 28, 29 and 30, equi-distant from the electric lamp 21, which, as above stated, is mounted at the central point of the base plate 12.

30 As a means for normally excluding the light of the lamp 20 from the chambers A, B and C, and at the same time permitting the chambers to be independently illuminated for the purpose of signaling the direction contemplated by the driver of the machine, there have been provided three shutters, designated individually by the numerals 35, 36 and 37, and respectively mounted for sliding movement across the 35 open end of the casings 28, 29 and 30. The shutters are similar in construction, and it is therefore deemed necessary to describe only one of them in detail. Reference will be had, therefore, particularly to Fig. 6. 40 By reference to this figure, it will be observed that a pair of spaced rods 38 and 39 are mounted at their terminals in sockets formed in the base plate 12 and face plate 14, these rods being arranged at opposite 45 sides of the casing. The shutter 40 is essentially a metallic plate, rectangular in shape, and equipped at each end with a pair of spaced rolled ears 41 and 42. The rolled ears of the shutters 40 encircle 50 the rods 38 and 39, and are designed to slide thereupon. A pair of coil springs 43 are mounted on the rods 38 and 39, each being disposed with one terminal in engagement with the base plate 12, and the other terminal fixed to the adjacent ear of the shutter. These spring members 43 are normally 55 designed to hold the shutters in closed position from the open end of the casing. Each shutter carries what may be termed armature disks, as indicated at 44.

As a means for electrically operating the shutters, there have been provided three electromagnets, individually designated by the numerals 45, 46 and 47, and respectively arranged in horizontal alignment with the disks of the shutters 35, 36 and 37. It will be observed that by energizing any one of the magnets, the shutter with which it is aligned will be pulled toward the magnet, thus opening the light chamber of the cas- 75 ing to which the shutter is attached.

As a means for attaching the base plate 12 to the automobile, a bracket of any suitable type, designated as an entirety by the numeral 48, may be employed.

The construction of the mechanical features of this invention being thus disclosed, it now remains to describe the wiring system which is diagrammatically illustrated in Fig. 7. In this figure, the numeral 60 designates the batteries, which are wired in series, and from which lead the positive conductor wire 61, and the negative conductor wire 62. The positive wire 61 is connected to the magnets 45, 46 and 47 by the wires 63, 64 and 65, while the negative wire 62 is connected to the magnets 45, 46 and 47, respectively, by the conductor wires 66, 67 and 68. Switches 69, 70 and 71, of the ordinary push button type, are interposed respectively in the wires 66, 67 and 68. The switches 69, 70 and 71 are placed within convenient reach of the driver, and may be equipped with any suitable characteristics to identify them. It will be observed that by these three switches, the driver of the machine may independently energize either one of the magnets 45, 46 or 47, to admit the light of the electric lamp into the several chambers A, B and C, referred to and described above. The lamp, designated in Fig. 7 by the numeral 21, is connected by the positive and negative wires 72 and 73, to the batteries 60 in the manner illustrated. A switch may be interposed in the lamp circuit, as at 74, thus enabling the driver to keep the lamp illuminated at all times, for the purpose of throwing a constant light on the tail plate or danger signal 23 and license plate 22.

As regards the operation of the signal, it is to be noted that if the driver of the signal carrying machine contemplates a right turn, the magnet 45 is energized by closing the circuit at the switch 69. When the magnet 45 is energized, the armature disk, carried on the shutter 35, will be drawn toward the magnet, thus withdrawing the shutter and admitting the light from the lamp 21 into the chamber A; consequently illuminating the arrow of the plate 24, and making the direction characteristic R discernible by the drivers of the oncoming vehicles. As soon as the circuit is broken, at 69, the spring 43 will return the shutter to closed position, 130

and the direction indicating plate 24 is again darkened. The manipulation of the device to illuminate the left turn and stop signals is similar, as will be observed by 5 reference to the drawings.

In reduction to practice, I have found that the form of my invention, illustrated in the drawings and referred to in the above description, as the preferred embodiment, is 10 the most efficient and practical; yet, realizing that the conditions concurrent with the adoption of my device will necessarily vary, I desire to emphasize the fact that various minor changes in details of construction, 15 proportion and arrangement of parts may be resorted to, when required, without sacrificing any of the advantages of my invention, as defined in the appended claims.

What is claimed is:

- 20 1. The combination in a direction indicating device including a base plate, of a cylindrical casing detachably secured to said plate, a plurality of variously colored glass plates mounted in said casing and provided 25 with direction indicating characteristics, an open ended housing for each of said plates, a sliding shutter for each of said housings, an electric lamp mounted centrally of said base plate, said shutters being normally dis- 30 posed to close the open end of the housing and to exclude the light from said electric lamp, an electromagnet for controlling the sliding movement of each of said shutters, said magnets being secured to the said base 35 plate, an independent electrical circuit for

each of said magnets, a lamp circuit including said lamp and a battery common to said circuits.

2. In a direction indicating signal, the combination with a casing, of an electric 40 lamp mounted centrally within said casing, a plurality of housings mounted within said casing, each of said housings open at one of its ends adjacent said lamp and provided with a direction indicating transparent wall, 45 shutters slidably mounted within said casing adjacent the open ends of said housings, means for normally closing said shutters and electrical means for opening said shutters to permit the access of light to said 50 housings.

3. In a direction indicating signal, a casing, an electric lamp mounted centrally within said casing, open ended housings mounted within said casing, direction indicating glass plates mounted in the faces of said housings, a pair of spaced rods mounted within said casing and adjacent the open ends of each of the housings, a shutter slidably mounted upon each pair of rods normally closing the adjacent housing, springs mounted upon said rods to normally hold said shutters in a closed position and electromagnets for opening said shutters. 55

In testimony whereof I affix my signature 60 in presence of two witnesses.

JAMES J. O'CONNELL.
